UNITED STATES PATENT OFFICE.

RALPH E. KIME, OF FOSTORIA, OHIO.

GARBAGE-RECEPTACLE.

1,102,275.

Specification of Letters Patent.

Patented July 7, 1914.

Application filed May 26, 1913. Serial No. 769,953.

To all whom it may concern:

Be it known that I, RALPH E. KIME, a citizen of the United States, residing at Fostoria, in the county of Seneca, State of Ohio, have invented certain new and useful Improvements in Garbage-Receptacles; and I do hereby declare the following to be a full, clear, and exact description of the invention, such as will enable others skilled in the art to which it appertains to make and use the same.

This invention relates to garbage receptacles.

The object of the invention resides in the provision of a garbage receptacle which will be thoroughly sanitary and is so constructed and arranged as to provide every facility for depositing garbage therein, and that while said garbage is thus being deposited practically all fumes and gases arising from the garbage in the receptacle will be prevented from escaping therefrom.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a vertical section of a garbage receptacle constructed in accordance with the invention, the parts being in position to receive a fresh deposit of garbage; Fig. 2, a view similar to Fig. 1 showing the parts in the position they would occupy to effect the complete discharge of a fresh supply of garbage from the upper section to the lower section of the receptacle; Fig. 3, a plan view of what is shown in Fig. 1 with the stripping and protecting member re- moved; Fig. 4, a view similar to Fig. 3 with the parts in the position shown in Fig. 2; Fig. 5, a section on the line 5—5 of Fig. 1, and Fig. 6, a detail perspective view of the spring-controlled slide.

Referring to the drawings the receptacle is shown as comprising a lower section A and an upper section B. The lower section A is in the form of a casing which has an open upper end and is supported upon legs 10. The upper section B is shown as including side members 11, 12, 13 and 14, and

a bottom 15. The horizontal dimensions of the section B are slightly greater than the horizontal dimensions of the section A so as to permit the section B being applied to the upper end of the section A in telescopic relation and with the bottom 15 resting upon the upper edges of the side members of the section A. The bottom 15 is provided with an opening 16 adjacent the side member 13 and secured to the inner sides of the side members 11, 12 and 13 in spaced relation to the bottom 15 are ribs 17, the exposed faces of which converge downwardly as at 18 so as to form substantially three walls of a hopper. Slidable between the ribs 17 and the bottom 15 and controlling the opening 16 is a slide plate 19. Suitably secured to the slide plate 19 at the end thereof remote from the side member 13 is an upstanding plate 20 to which is secured one end of a rod 21, said rod extending through an opening 22 in the side member 14 and terminating in an enlarged head 23 disposed exteriorally of the section B. Disposed between the upstanding plate 20 and the side member 14 is a bow spring 24 the terminals of which are provided with openings 25 through which the rod 21 extends. The ends of this spring bear respectively against the inner side of the side member 14 and against the upstanding plate 20 and said spring serves to normally hold the plate 19 in closing position with respect to the opening 16. Mounted within the section B is an L-shaped member including a vertical arm 26 and a horizontal arm 27, the lower edge of the vertical arm 26 engaging the upper side of the plate 19 and serving as a stripping member to force material from the plate through the opening 16. The horizontal arm 27 of said L-shaped member completely covers the rod 21 and spring 24 serves to efficiently protect same. The upper end of the section B is adapted to be closed by a horizontal cover 28 and this cover is supported in open position by means of a finger plate 29 secured to the outer side of the side member 14.

If it is desired to deposit garbage in the receptacle same is first applied upon the slide 19 between the arm 26 of the L-shaped member and the ribs 17. The cover 28 is then closed and the rod 21 moved outwardly against the influence of the spring 24. This movement of the rod 21 will cause a corresponding movement of the slide 19 and thus

open communication between the sections A and B through the opening 16. During this movement of the slide 19 the arm 26 will scrape all the material therefrom and such material will thus fall under the influence of gravity into the receptacle A. The rod 21 is then released to the influence of the spring 24 when the slide 19 will be moved to a position to close the opening 16 and prevent any odors escaping from the section A to the atmosphere when the hinged cover 28 is again opened.

What I claim is:—

1. In a device of the class described, the combination of a receptacle including upper and lower detachable sections, the upper section having its side portions telescopically engaged over the side walls of the lower section, a bottom included in the upper section and provided with an opening said bottom engaging the upper edges of the side members of the lower section and resting thereon, a slide plate mounted in the upper section above the bottom for closing said opening, a rod having one end secured to said plate and slidable through an opening in a side wall of the upper section, a bow spring having its terminals provided with openings through which said rod is engaged, said spring bearing respectively

against a side wall of the upper section against the slide plate and normally holding the latter in position to close the opening, a stripping member engaging the slide plate and adapted to remove material therefrom when said plate is moved from closing relation with respect to the opening in the bottom, and a hinge cover for closing the upper end of said upper section.

2. In a device of the class described, the combination of a receptacle, a horizontal partition in said receptacle provided with an opening, a vertical partition in the receptacle above the horizontal partition and having its lower edge spaced from the upper side of the horizontal partition, a slide mounted in the receptacle for controlling said opening and movable between the horizontal and vertical partition with its upper side in engagement with the lower edge of the vertical partition, means for normally holding said slide in position to close the opening, and a hinged cover for closing said receptacle.

In testimony whereof, I affix my signature, in the presence of two witnesses.

RALPH E. KIME.
